UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-DRAWING MACHINE.

1,047,168.

Specification of Letters Patent. Patented Dec. 17, 1912.

Application filed January 25, 1909. Serial No. 474,129.

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Drawing Machines, of which the following is a specification, accompanied by drawings forming a part of the same, in 10 which—

Figure 1 represents a plan view of a wire drawing machine embodying my improvement. Fig. 2 is a side elevation of the same: Fig. 3 is a side elevation partly shown in 15 section, and Fig. 4 is a detached plan view of a portion of the operative parts of the machine.

Similar reference letters and figures refer to similar parts in the different views. 20 My present invention relates to that class of wire drawing machines in which a rotating block is employed, whereon the wire is wound as it is drawn through a reducing die, and it has for its objects to provide an 25 improved mechanism for connecting and disconnecting the wire drawing block with its driving mechanism; to provide means for automatically stopping the block after the initial draft of wire through the die, and 30 further to provide means for automatically stopping the block when the progress of the wire to the reducing block is impeded by kinks or otherwise, and I accomplish these 35 objects by the construction and arrangement of parts as hereinafter described and pointed out in the annexed claims.

Referring to the accompanying drawings, 1 denotes a portion of the framework of the machine, 2 a rotating wire drawing block 40 which is operatively connected with a vertical shaft 3, in the present instance, by means of a clutch mechanism comprising a jaw 4 on the under side of the wire drawing block, which is engaged by a jaw 5 carried 45 by the vertical shaft 3, which in turn is driven through beveled gears 6 and 7 from a driving shaft 8. The under side of the block 2 is provided with an annular track 9, in position to contact with a pair of friction 50 rolls 10, 10, and be lifted from the clutching mechanism, thereby disconnecting from the driving shaft as the rolls 10, 10, are raised. The friction rolls 10, 10, are supported in a yoke 11, which has gudgeons or

bearings 12, 12, supported in seats 13, forming 55 a part of the framework of the machine.

The yoke 11 is provided with an arm 14, the free end of which is pivotally connected by a link 15 with an arm 16 attached to a rock shaft 17. A spiral spring 18 connects 60 the arm 14 with the fixed framework of the machine, with the tension of the spring applied to depress the free end of the arm 14, the spring having sufficient force to raise the friction rolls 10 against the annular 65 track 9 and lift the rotating wire drawing block 2 from its clutch connection with the shaft 3. The outer end of the rocking shaft 17 is polygonal, as shown at 19, Fig. 2, and carries a two-armed foot treadle 20. By depressing the end 21 of the foot treadle, the shaft 17 is rocked to carry the arms 14 and 16 and link 15 into the positions shown in Fig. 2, with the upper end of the arm 16 bearing against a stop 22 projecting from 70 the framework of the machine, said stop receiving the pressure exerted by the spring 18 to hold the center of the pivotal pin 23 slightly to the right of a vertical line connecting the center of the rocking shaft 17 75 and the pivotal pin 24, thereby holding the parts in position against accidental displacement, with the friction rolls 10 depressed to allow the wire drawing block 2 to be engaged by its clutching mechanism. 80

In order to disconnect the block 2 from its driving mechanism, the end 25 of the two-armed treadle is depressed sufficiently to carry the pivotal pin 23 past the center line, joining the pin 24 and shaft 17, when the 90 tension of the spiral spring 18 will continue the rocking motion of the shaft 17, bringing the link 15 and arm 16 into the position denoted by the dot and dash lines 26, thereby carrying the friction rolls 10 against the annular track 9 and lifting the wire drawing block 2 sufficiently to disengage it from its clutching mechanism. A very slight angular movement of the rocking shaft 17 is all 95 that is required to bring the spring 18 into 100 action in disengaging the rotating block 2.

The wire drawing block 2 is provided with an opening 27 to receive a hook 28 to which a chain 29 is attached, provided at its end with a gripping mechanism 30, by which 105 the end of the wire 31 to be drawn may be seized and drawn through a reducing die 32, held in a die box 33 far enough to be seized

by a clamping mechanism 34, or in the position shown in Fig. 1. When this is accomplished, the rotation of the wire drawing block 2 is automatically stopped by means of a spur 35, projecting from the outside of the wire drawing hook 28, coming in contact with a radial arm 36, which is carried upon the upper end of a vertical rocking shaft 37. The lower end of the shaft 37 is provided with a radial arm 38, the free end of which is pivotally connected by means of a link 39 with a radial arm 40 on the lower end of the rocking shaft 41. The rocking shaft 41 is provided with a radial arm 42.

15 The arm 42 is pivotally connected by a link 43 with a lever 44, capable of a swinging movement upon a short vertical shaft 45, journaled in a bearing 46 in the framework of the machine. Pivoted to the free end of 20 the swinging lever 44 are a pair of parallel bars 47 and 48, capable of sliding in ways formed in a vertical wing piece 49, projecting from the inside of the frame. Pivoted at 50, between the bars 47 and 48, is a pawl 25 51. In its normal position the pawl 51 is held with its end 52 in alignment with the link 15. The pawl 51 is maintained in this position by means of a spiral spring 53, enclosing a rod 54, which passes through a 30 yoke 55 and carries on its outer end a nut 56. The nut 56 limits the swinging movement of the pawl 51 under the tension of the spring 53.

When the spur 35 rocks the shaft 37 by its 35 contact with the arm 36, it draws the link 39 in the direction of the arrow *a* and, through the intermediate mechanism already described, moves the parallel bars 47 and 48 in the direction of the arrow *b*, Fig. 4, causing the end 52 of the pawl 51 to press against the side of the link 15 and swing it past the center line between the rocking shaft 17 and the pivot 24, so that the spring 18 will instantly act to throw the link 15 into the 40 position indicated by the dot and dash lines 26, thereby lifting the friction rolls 10 sufficiently to raise the rotating block 2 out of engagement with the shaft 3. This stops the further winding of the wire 31 and disconnects the block 2, so the end of the wire may 45 be released from the grip 30 and seized by the grip 34. The foot treadle 20 is then rocked by the depression of its end 21 into the position shown in Fig. 2, thereby lowering the block 2 into operative relation with the driving power.

The vertical rocking shaft 41, in addition to the radial arms 40 and 42 is provided with a radial arm 57, provided with a notch 58 in its upper surface, through which the wire 31 is conducted to the die box 33. The notch 58 is restricted to substantially the size of the wire, so that a kink or bend in the wire, like that shown by the broken lines at 59, Fig. 1, for example, which

would impede the passage of the wire through the die will also act upon the radial arm 57 to swing it in the direction of the arrow *c*, Fig. 1, thereby rocking the shaft 41, in the same manner as it would be rocked by the contact of the spur 35 against the radial arm 36, as above described, causing the parallel bars 47 and 48 and pawl 51 to be moved in the direction of the arrow *b*, Fig. 4. This movement of the pawl 51 against the side of the link 15 will throw the link 15 and arm 16 past the center line, so that the spring 18 will act to throw the link 15 and arm 16 into the position denoted by the dot and dash lines 26, Fig. 2, thereby disconnecting the drawing block 2.

The link 15 and arm 16 form substantially a toggle-joint connection between the rocking shaft 17 and the free end of the arm 14, and as the pivotal connection 23 is carried past the center line between the axes of 20 17 and 24, while the block is in an operative position, it requires but a slight pressure either against the link 15 by means of the pawl 51 or upon the end 25 of the foot 25 treadle by the operator to immediately bring the spring 18 into action to disconnect the wire drawing block from its driving power.

Attached to the shaft 45 by means of a spline 60 is a disk 61 provided with a depending clutch tooth 62, adapted to engage a shoulder 63 on the lever 44. The disk 61 is provided with an arm 64, which is connected with the rigid framework of the machine by a spiral spring 65. To the upper end of the vertical shaft 45 is rigidly attached a radial arm 66, to the free end of which the die box 33 has a pivotal connection. The radial arm 66 is capable of a slight swinging movement within an opening 67 in the framework of the machine, and, when the drawing block is not in use, the radial arm 66 is normally held against the side 68 of the opening 67 by means of the spiral spring 65, but when the wire 31 is being drawn through the die, the tensile strain applied to the wire will draw the die box 33 and arm 66 into the position shown in Fig. 1, in which the swinging movement of the arm 66 is limited by the side 69 of the opening 67. In this position the shoulder 63 of the lever 44 is held against the clutch tooth 62 by means of a spiral spring 70, which connects the lever 44 with the fixed framework of the machine.

Should a breakage occur in the wire between the drawing block 2 and the die, the tensile strain upon the wire would be removed, and the vertical shaft 45 will be instantly rocked by the tension of the spring 65, causing the lever 44 to be swung by means of the connection between the clutch tooth 62 and the shoulder 63, again moving the parallel bars 47 and 48 in the direction of the arrow *b*, Fig. 4, and carrying the

pawl 51 against the link 15 to throw the toggle-joint past the center and cause the spring 18 to disconnect the wire drawing block 2 from the driving power.

- 5 By the above described mechanism the wire drawing block will become stopped under the following conditions; first, at the beginning of its rotation when the spur 35 contacts with the radial arm 36, enabling 10 the end of the wire to be transferred from the gripping mechanism 30 to the clamping mechanism 34; second, whenever a kink or obstruction in the wire is too large to pass through the notch 58; and, third, whenever 15 a breakage occurs in the wire between the wire drawing block and the die box.

In the operation of stopping the drawing block by means of the above described mechanism, the pawl 51 has its oblique edge 71 brought into contact with a fixed stud 72, which serves to rock the pawl 51 on its pivot 50, in order to swing the end of the pawl which contacts with the link 15 out of alignment with the link, to allow the shaft 20 25 17 to be rocked by means of the foot treadle 20 into the position shown in Fig. 2, for the purpose of starting the wire drawing block without reversing the stopping mechanism.

I claim:

- 30 1. In a wire drawing machine, comprising a rotatable block, and a clutching mechanism between said block and the driving power, the combination with the clutching mechanism, of a clutch disengaging mechanism, comprising a toggle joint and spring operatively connected with said toggle joint, a movable die block and mechanism operatively connected with said die block for actuating said toggle joint to disengage the clutching mechanism when the wire breaks.
2. In a wire drawing mechanism, comprising a rotatable block and a clutching mechanism between said block and the driving power, the combination of a movable die 45 box, a motor spring for disengaging said

clutching mechanism, a toggle joint mechanism for engaging said clutching mechanism, and intermediate operative connections between said movable die box and said toggle joint mechanism for actuating the latter 50 to disengage the clutching mechanism when the wire breaks.

3. In a wire drawing mechanism, comprising a rotatable block and a clutching mechanism between said block and the driving power, the combination of a movable die box, a spring applied to said die box to resist the strain of the wire, a toggle joint mechanism for disengaging said clutching mechanism, and mechanism actuated by said die box spring for operating said toggle joint mechanism to release the clutching mechanism when the die box is relieved of the strain of the wire.

4. The combination with a die box, a wire drawing block and a clutching mechanism between said block and the driving power, of a clutch disengaging mechanism, a motor spring therefor and means for bringing said motor spring into operative relation to said disengaging mechanism, comprising a toggle joint, mechanism for tripping said toggle joint, a spring for actuating said tripping mechanism, and means for holding said spring in a state of tension determined by 75 the tensile strain of the wire to be drawn exerted upon the die box.

5. In a wire drawing machine, the combination with a rotatable block and a clutching mechanism therefor, of mechanism 80 for disengaging the clutching members, a motor spring therefor, a toggle joint for holding said spring in a state of tension, and means for tripping said toggle joint determined by the tensile strain upon the wire. 85

Dated this 22nd day of January 1909.

ELBERT H. CARROLL.
